UNITED STATES PATENT OFFICE.

RUSSELL T. MANNING, OF MINNEAPOLIS, MINNESOTA.

DESIGN FOR A CIGAR LIGHTER.

Application filed February 25, 1926. Serial No. 16,666. Term of patent 7 years.

To all whom it may concern:

Be it known that I, RUSSELL T. MANNING, a citizen of the United States, residing at Minneapolis, in the county of Hennepin and State of Minnesota, have invented a new, original, and ornamental Design for Cigar Lighter, of which the following is a specification, reference being had to the accompanying drawing, forming part thereof.

The single view of the drawing is a perspective of a cigar lighter, showing my new design.

I claim:

The ornamental design for a cigar lighter, as shown.

RUSSELL T. MANNING.
